UNITED STATES PATENT OFFICE.

ALBERT J. WAYMAN, OF EAST PALESTINE, OHIO, ASSIGNOR TO THE EFFICIENCY ELECTRIC COMPANY, OF EAST PALESTINE, OHIO, A CORPORATION OF OHIO.

PIPE-HANGER.

1,255,674.

Specification of Letters Patent.

Patented Feb. 5, 1918.

Application filed September 24, 1917. Serial No. 192,968.

To all whom it may concern:

Be it known that I, ALBERT J. WAYMAN, a citizen of the United States, residing at East Palestine, in the county of Columbiana and State of Ohio, have invented certain new and useful Improvements in Pipe-Hangers; and I do hereby declare the following to be a full, clear, and exact description of the invention, such as will enable others skilled in the art to which it appertains to make and use the same.

My invention relates to hangers for conduits and pipes.

Its object is to provide a device whose parts may be quickly assembled and readily applied to secure a pipe or conduit in place.

To this end it comprises the combinations and parts recited in the appended claims.

In the accompanying drawings:-

Figure 1 is a side elevation of the device applied to a girder which is shown in section;

Fig. 2 is a perspective view;

Figs. 3 and 4 are details of different forms of the hanger embodying the same principle.

In the drawing 1 represents a conduit or pipe, 2 a hanger loop, and 3 a locking or wedging tongue which secures loop about the pipe or conduit. The loop has the customary opposed web pieces which are perforated to receive a securing bolt 5. These web pieces are slightly separated to readily receive the locking tongue 3. The locking tongue has an elongated perforation 6 which registers with the perforation in the web pieces so that the locking tongue may move horizontally with relation to the screw bolt 5. The locking tongue has an inclined face adapted to take over the base of a girder as illustrated. I preferably reduce the opposite or head end.

When the parts are assembled each lock-

ing or wedging tongue is driven forward by hammering upon its short end or head forcing the inclined face of the locking tongue up the adjacent base of the girder and thus drawing each loop 2 tightly about the pipe or conduit.

At 7 I have shown an additional securing device, a strip of metal carried upon the screw bolt 5 and adapted to be bent across the face of the head of the locking tongue to secure it in place after it is driven home.

In Fig. 3 is shown one form of loop with web pieces at the top, and in Fig. 4 is shown another form of loop with web pieces at both the top and bottom.

I claim:-

1. In a pipe-hanger, the combination with a hanger-loop having opposed web pieces, of a locking tongue having an inclined face to engage a girder or other support and adapted to operate between the web pieces.

2. In a pipe-hanger, the combination of a hanger-loop having web pieces, and a wedging tongue carried between the web pieces and adapted to be hammered into locking position.

3. In a pipe-hanger, the combination of a loop-hanger, perforating web pieces, a securing bolt passing through the perforations, and a locking tongue having an elongated perforation through which the securing bolt passes, a projecting part forming a head on the other side of the web pieces.

4. In a pipe-hanger, the combination of a hanger-loop having web pieces, a wedging tongue lying between the web pieces and a guard comprising a sheet of metal adapted to be bent around the projecting head of the tongue after it is adjusted to the locking position.

In testimony whereof I affix my signature.

ALBERT J. WAYMAN.
